UNITED STATES PATENT OFFICE.

FREDERICK HARDY, OF BIRMINGHAM, ALABAMA.

MATCH-SAFE.

SPECIFICATION forming part of Letters Patent No. 596,404, dated December 28, 1897.

Application filed October 22, 1896. Serial No. 609,733. (No model.)

To all whom it may concern:

Be it known that I, FREDERICK HARDY, residing at Birmingham, in the county of Jefferson and State of Alabama, have invented 5 a new and useful Match-Safe, of which the following is a specification.

This invention relates generally to match-safes, and more particularly to one from which the matches are fed one at a time, the object 10 of the invention being to provide a simple and efficient device which will prevent more than one match being fed at a time, and, furthermore, will prevent the matches from clogging.

15 Another object is to provide against any partial movement of the parts by locking the said parts, so that a complete operation is necessary in order to return the parts to their normal position.

20 Another object of the invention is to provide a suitable scratching device in connection with the delivery-tube whereby as the match is drawn out it will be ignited.

Another object of the invention is to provide 25 a locking top in order to prevent tampering with the device.

Another object is to provide for the even and steady feed of the matches, whereby the efficient operation of the device is insured.

30 With these various objects in view my invention consists in the peculiar construction of the various parts and in their novel combination or arrangement, all of which will be fully described hereinafter and pointed out 35 in the claims.

In the drawings forming a part of this specification, Figure 1 is a perspective view of my device. Fig. 2 is a vertical longitudinal section. Fig. 3 is a transverse section of Fig. 2.

40 Fig. 4 is an interior perspective view, one side of the box or case being removed. Fig. 5 is a detail view of the hinged stop-board. Fig. 6 is a detail view of the slotted guide-plate. Fig. 7 is a detail view of the plunger and at- 45 tached parts. Fig. 8 is a detail view of the rake. Fig. 9 is a detail perspective view of the end of the inclined feed-board.

In carrying out my invention I employ a box or case A, provided with a top or cover 50 B, which cover slides in grooves in the upper edges of the sides and is locked therein by

means of a suitable spring-rod, which spring-rod is released, when desired, by means of a key introduced in the keyhole C.

The box or case A is constructed with a 55 false bottom D, said false bottom having a transverse recess or channel E, in which works a plunger F, having the head G at the rear end, and between the said head and the opposite side of the case is arranged a coil- 60 spring H, surrounding said plunger-rod. A flat spring I is secured in the bottom of the recess or channel E and at its rear end is provided with an upwardly-projecting tongue K, and adjacent to the rear end said spring 65 is formed with an upward bend or offset portion L, as most clearly shown in Fig. 3. A presser-finger M is arranged upon the rear end of the head G, said finger projecting up above the head and sliding in the slot N, pro- 70 duced in the guide-plate N', said slot N ex- tending to a point near the forward end of the plate. Parallel with the slot N is a shorter slot N², through which pass the bevelled depending fingers N³, formed upon the 75 lower end of the inclined feed-board N⁴, the upper end of said board being rigidly at- tached to the end of the box or case and upon 80 which the matches are adapted to rest while held within the safe. Upwardly-projecting 85 lugs N⁵ are formed upon the opposite side of the slot, said lugs being preferably punched up from the body of the guide-plate N'.

It will of course be understood that there is an opening O in the side of the case at the 85 forward end of the guide-plate, and upon the exterior of the case is arranged the delivery chute or tube O', having the spring O² in the bottom thereof, which is adapted to press the head of the match against the roughened sur- 90 face O³, produced upon the top of the delivery-tube, so that as the match is drawn from the delivery-chute the head engaging the rough- ened surface O³ will be ignited.

Now it is clear that as thus far described 95 the matches placed upon the inclined feed- board will gravitate to the guide-plate and will be stopped by means of the lugs N⁵, and as the plunger is drawn outwardly the presser- finger will contact with the match and force 100 the same through the opening O and delivery chute or tube O'.

In order to prevent the matches clogging, and also to prevent more than one match being operated upon at the same time, I employ a fall-board P, which is hinged between the sides of the case at the upper end and swings freely at its lower end, said board having a curved groove P' produced in the edge thereof sufficiently large to permit the movement of a match therethrough. A plate P² is secured to the lower edge of the board P, said plate having a shoulder P⁴ near the lower end and a shoulder P⁵ near the forward end, said shoulders being produced by the cut-out portions P⁶ P⁷, respectively, and at the rear end of the plate is provided a catch-finger P⁸, which is adapted to engage the finger K upon the end of the spring-plate I. The lower end of the fall-board P is normally held by a spring Q, so that the plate P² will close the slot of the guide-plate and prevent the match falling therethrough, the forward movement of the lower end of the board being limited by means of the lugs N⁵, which also limit the rearward movement of the matches.

In order to insure the even and steady feed of the matches along the feed-board, I employ a rake R, consisting, essentially, of a plate having the forward end thereof bent down toward the feed-plate, as shown at R', the opposite end of said plate having a T-shaped head R², adapted to engage the slot R³, produced in the fall-board and extending nearly to the lower end thereof, by means of which the said rake is given a backward-and-forward movement as the fall-board P is swung back and forth upon its pivots, and in order to hold the rake down upon the matches, I provide a spring R⁴, which is attached to the top of the plate near the forward end, the opposite end of said spring bearing against the top of the box, as most clearly shown in Fig. 2.

Now in operation the cover is unlocked, opened, and the matches placed upon the inclined feed-board N⁴ and the rake placed in position upon the top of said matches. The cover of the box is then replaced and locked, and the device is ready for use. The normal position of the fall-board P, against which the matches fall, is such that the plate P² upon the bottom of said board covers the slotted portion of the guide-plate, thereby preventing the matches falling into the said slot. When it is desired to draw a match from the safe, the knob or rod upon the forward end of the plunger is grasped and pulled outwardly, which movement causes the presser-finger M at the end of the plunger to come in contact with the lowest match, carrying the said match forward and projecting the same through the opening O into the delivery chute or tube O'. As the plunger is moved forwardly the fall-board moves toward the end of the inclined feed-board, being so employed by means of the spring Q that it is impossible for another match to fall upon the guide-plate. As the head of the plunger is moved forward it contacts with the depend-

ing beveled teeth formed upon the end of the feed-board, and consequently vibrates the said feed-board sufficiently to cause the matches to roll down the same. At the same time the rake is agitated, inasmuch as it is connected with the fall-board, so that as the said board moves the rake is also moved, and this movement taking place simultaneously with the movement of the feed-board insures the steady and even feed of the matches toward the guide-plate. A complete movement of the plunger causes the match to be forced partially through the delivery-tube, said match being held in such position by means of the spring O², and by grasping the end of the match with the fingers and drawing the same through the delivery-tube the head will be ignited, inasmuch as it will contact with the roughened or abrasive surface O³, formed upon the interior of the delivery-tube. When the plunger is moved forward and the fall-board swung into operation so as to close the opening, the end of the spring I passes under the rearwardly-projecting tongue upon the end of the plate P², in which position the shoulder P⁴ prevents the return of the plunger, which cannot be returned to place until it is drawn completely outward, after which it can be readily returned to its normal position, inasmuch as the head of the plunger coming in contact with the shoulder P⁵ thereby moves the fall-board sufficiently to permit the end of the spring I to engage the projecting tongue upon the end of the plate P², which holds the fall-board in such position that the plunger-head can pass the shoulder P⁴ in returning to place. After one match has been withdrawn and the channel has been opened by the return of the plunger to place, another match drops into position to be withdrawn, the closing of the channel during the withdrawal of a match making it impossible for more than one match at a time to get into the channel.

It will be also understood that the top of the box or case can be of glass.

Furthermore, instead of attaching the box or case rigidly to a base or rigid object, it can be so attached as to have a slight movement whereby the box or case can be shaken slightly in order to facilitate the feeding of the matches whenever desired.

It will thus be seen that I provide an exceedingly cheap and simple device, capable of easy and accurate operation, and one in which all of the parts perform their various functions in a highly-efficient manner.

It will also be noticed that I provide a safe from which only one match can be withdrawn at a time, and also a match-safe which will absolutely prevent clogging and accidents of any kind whatever.

Having thus described my invention, what I claim as new, and desire to secure by Letters Patent, is—

1. In a match-safe, the combination with the box or case of the feed-plunger working

thereon, the inclined feed-board, the pivoted fall-board and the rake connected with the fall-board, said fall-board, rake and feed-board being operated by the movement of the 5 feed-plunger, substantially as shown and described.

2. In a match-safe, the combination with the box or case of the feed-plunger working therein, the inclined feed-board, the fall- 10 board having a groove in the lower edge and provided with a plate having a plurality of shoulders thereon, the presser-finger and spring all arranged and adapted to operate substantially as shown and described.

15 3. In a match-safe, the combination with a box or case of the plunger arranged therein, having a presser-finger at the rear end of the head of said plunger, the base-spring having a tongue projecting upwardly from the rear 20 end thereof, the slotted guide-plate having the stop-lugs, fall-board having a groove at the lower edge, the plate arranged upon the bottom of the fall-board and having a plurality of shoulders and cut-out portions, the 25 inclined feed-board and the rake connecting with the fall-board adapted to lie upon the

matches and hold them upon the feed-board, substantially as shown and described.

4. In a match-safe, the combination with the box or case of the inclined feed-board 30 having the depending teeth, the plunger having a head provided with the presser-finger, the slotted guide-plate having the stop-lugs, the base-spring having upwardly-projecting finger or tongue, the pivoted fall-board having a groove in the lower edge, the plate attached to said lower edge and having a plurality of shoulders and cut-out portions, the 35 spring bearing upon the lower end of said fall-board, said fall-board being slotted as described, the rake having a T-shaped head adapted to engage the said slot and provided with the spring adapted to hold the said rake in place upon the matches and the delivery- 40 chute or tongue having an abrasive surface, 45 all of said parts being arranged and adapted to operate substantially as shown and described.
